UNITED STATES PATENT OFFICE.

LOUIS MOEN, OF ULEN, MINNESOTA.

KEY HOLDER.

1,410,213.

Specification of Letters Patent. Patented Mar. 21, 1922.

Application filed April 29, 1921. Serial No. 465,380.

To all whom it may concern:

Be it known that I, LOUIS MOEN, a citizen of the United States, residing at Ulen, in the county of Clay, State of Minnesota, have invented certain new and useful Improvements in Key Holders; and I do hereby declare the following to be a full, clear, and exact description of the invention, such as will enable others skilled in the art to 10 which it appertains to make and use the same.

This invention relates to new and useful improvements in key holders and particularly to door key holders.

15 One object of the invention is to provide a simple and cheap device which can be easily and quickly applied to the knob spindle of a door and engaged through the eye of the key to hold the key against turning 20 movement from without.

Another object is to provide a key holder which is applicable to door knobs and keys of different sizes, and in instances where the keys are at greater or lesser distances 25 from the knob.

Other objects and advantages will be apparent from the following description when taken in connection with the accompanying drawing.

30 In the drawing:

Figure 1 is a front elevation of the invention in connection with the knob and key of a door, the knob and key being broken away.

35 Figure 2 is a side elevation of the same.

Referring particularly to the accompanying drawing, 10 represents a portion of a door, 11 the knob, 12, the spindle of the knob, and 13 the key, which latter has the 40 usual eye 15.

The key holder is preferably formed from a single length of suitably stiff wire and includes the parallel leg portions 16, connected at one end by the bight portion, said 45 legs being arranged to straddle the knob spindle 12, while the bight portion stands above the said spindle. The other end of each leg 16 is bent into a loop 18, the loop

being extended outwardly and disposed in a vertical plane. The wire is then bent 50 around each leg and then directed outwardly in the form of a hook 19.

It will be noted that the loops 18 are disposed in parallel vertical planes so that they may be easily grasped between the thumb 55 and finger of the hand of the operator, to press them together when operating the device to engage or disengage the hooks with respect to the eye of the key.

The wire is preferably flexible so that the 60 legs may be flexed when the loops are pressed inwardly.

In the applied position of the device, it will be noted that the legs are disposed outwardly of the eye, and at the opposite sides 65 thereof, while the hooks engage within the eye and with the side portions thereof. The flexibility of the legs serves to maintain the hooks in firm gripping engagement with the eye portion of the key, thus effectively preventing 70 the key being turned, in the lock, by an instrument inserted in the keyhole from the outside of the door.

What is claimed is:

1. A key holder formed from a length of 75 stiff and flexible wire and including a pair of parallel legs connected at one end by a bight portion, the other end of each leg being twisted about the body of the leg and having its tip formed into an outwardly directed key eye engaging hook.

2. A key holder formed from a length of 80 stiff and flexible wire and including a pair of parallel legs connected by a curved bight portion, the other ends of the legs being 85 formed into outwardly extending vertical loops and twisted about the bodies of the legs inwardly of the loops, with the tips of said ends bent into hooks, said hooks being directed away from each other.

In testimony whereof, I affix my signature, in the presence of two witnesses.

LOUIS MOEN.

Witnesses:

L. LOFGREN,
JOHN TOVS.
